UNITED STATES PATENT OFFICE.

WALTER E. MURRAY, OF FORT DODGE, NEBRASKA, ASSIGNOR TO ANAKIN LOCK & ALARM CO., OF CHICAGO, ILLINOIS, A CORPORATION OF DELAWARE.

SAFE-DOOR ATTACHMENT.

Application filed December 23, 1922. Serial No. 608,622.

To all whom it may concern:

Be it known that I, WALTER E. MURRAY, a citizen of the United States, residing at Fort Dodge, in the county of Webster and 5 State of Nebraska, have invented certain new and useful Improvements in Safe-Door Attachments, of which the following is a specification.

The present invention relates to improvements in safe door attachment and aims to vary and rearrange certain present constructions in order to render it impossible for avoiding the unlocking of the door from the interior of a bank safety vault or the like. 10 Bank robbers have frequently resorted to the practice of driving all of the bank officials at the point of a gun into the vault after removing all of the money and valuables and then locking these same officials to 15 avoid escape and the possibility of sounding an alarm before the bandits have effected their escape and eluded any possible immediate pursuers.

The present time locks provide for the 20 opening of the safe from the interior but the present mechanism for effecting a tight closure of the vault or safe door renders it impracticable to open the door, even though unlocked and it is the object of the invention 25 to remove this barrier provided by the door closing mechanism.

Other objects of the invention are to accomplish this result without requiring any great change in standard constructions and 30 in modifying and rearranging a part of the present construction so that it may replace the present device at small cost and will afford the same cooperation with associated elements so as to tightly close the door to 35 avoid the flowing of nitroglycerin liquid beneath the door flanges or laminations.

Still further objects of the invention are to provide a device that may be dismounted from its normal, operative position and 40 stored or hidden away in the bank during banking hours and only replaced at the end of the banking day when the vault or safe door is to be closed and locked for the night; this removable part being necessary to the 45 door closing mechanism and such that the door cannot be barred by the closing mechanism without its use; to enable the attention in removing and replacing this part to be

conducted without burden or possible forgetfulness, and to make the construction of 55 such a character as to afford no expedient to the thieves to lock the door from without.

With the foregoing and other objects in view, the invention will be more fully described hereinafter, and will be more particularly pointed out in the claims appended hereto.

In the drawings, wherein like symbols refer to like or corresponding parts throughout the several views, 65

Figure 1 is a front view of the vault door showing the door closed.

Figure 2 is a similar view with the door partly open and the front of the vault indicated in section. 70

Figure 3 is an enlarged side view of the new attachment.

Figure 4 is a front view of the socket member.

Figure 5 is a top view of the attachment, 75 and

Figure 6 is a perspective view of the same.

Referring more particularly to the drawings, 7 designates the face panel of a vault and 8 the door which is composed as usual of laminated plates 9 shown in Figure 2. These plates are of steel and they cooperate with similar faces in the panel 7, the meeting faces of both door and panel being ground to fit accurately and faithfully so that no crevices are presented for the introduction of the liquid nitroglycerin. 85

The door is movably suspended upon the large and heavy hinge 10 having arms 11 at its outermost ends extending toward the center of the door and other arms 12 inwardly of the arms 11 and extending in an opposite direction. Both sets of arms are perforated to receive respectively the pivot pins 13 and 14 by which the hinge structure is secured to the straps 15 riveted or otherwise affixed to the door 8 and to the straps 16 secured in a like manner to the panel 7. The hinge structure thus described operates in a well known manner to permit the door 8 to swing about the vertical pivots 13 and to thereby accommodate itself closely to the surface of the panel against which the laminated plates 9 engage and in this way a tight fit is effected. 100

The combination locking mechanism is

indicated generally at 17 although this forms no part of the invention and is not therefore illustrated in detail.

The mechanism for tightly closing the door is also of the usual construction and is shown more clearly and described as follows:—

The hand wheel is indicated at 18 and extends into the casing 19 in a customary manner and in accordance with the general construction, within the casing is a worm gear mechanism, also well known, by which the rotation of the hand wheel 18 communicates a like movement to the shaft 20 which extends horizontally and diametrically across the door 8 and is carried in the brackets 21 affixed to the door with projecting ends beyond the brackets and beyond the edge of the door having the crank arms 22 and the eccentric pins 23. The eccentric pin at the right side of Figure 1 is in register at all times with its socket member 24. This member is pivotally attached by means of a pin 25 to an upper arm 26 and lower arm 27, these arms being bolted to the panel as by the fastenings indicated at 28. The member 24 is thus free to swing with the door 8.

At the left side of the panel, which is the free open edge of the door, a slightly different construction obtains in that the crank or eccentric pin 23 must become detached from its abutment member in order to allow the opening of the door. For this purpose a block 29 is carried by the panel 7 having a slot 30 open at its upper end to receive the crank pin 23 and the block is affixed to the door.

By engaging the pin 23 with the slot 30 and then further rotating the hand wheel 18 it will be apparent that the engagement of the pin with the wall of the slot 30 and the engagement of the opposite crank pin with its member 24 will cause the door to be forced inwardly in a direct axial line such as will cause the faces of the various plates 9 of the door to accurately and closely fit against the similar surface of the panel 7 provided to receive them.

However the engagement of the left crank pin 23 prevents the opening of the door 8 from within the vault because the door closing mechanism has no operating member on the interior side of the door. This door closing mechanism, for this reason has, in the past, been highly useful to the successful escape of bandits and bank thieves by reason of preventing the incarcerated officials from getting through the door until the robbers had made off to some distance.

Now I propose to modify this existing and standard construction in the manner shown in Figures 3 to 6 inclusive in which the slotted block 29 is made separate from a socket member 31 and removably attached

thereto by the use of right angularly disposed flanges 32 along one edge of the block 29 adapted to fit down into the socket 33 of the socket member which is closed at its base to support the block and has a slot 34 in its front wall open at the top to receive the block. The socket member is secured to the panel 7 as by the use of countersunk screws 35. The construction is such, as apparent from Figures 3 and 6, as to enable the lifting of the block 29 out of the socket member without difficulty or inconvenience, while the construction presented exhibits all of the necessary strength and sturdiness to withstand the pressure put upon this device in effecting a closing of the door.

Now the improved device has this very desirable advantage that it enables the block 29 to be removed by the cashier in the morning when first opening the safe or vault door and the cashier may conceal this block 29 all during banking hours in some convenient place where hold-up men would not be apt to discover it. In the absence of the block 29 the door 8 could be closed and locked by the combination locks but immediately those confined could open the door without any hindrance from the door closing mechanism, inasmuch as the crank or eccentric pin 23 would have no engagement.

The flanges 32 upon the block 29 are thick and substantial and they present relatively large surfaces against the walls of the socket 33 and the structure of socket and plug is such that the same durability and strength obtains in this divided structure as heretofore existing in the permanent one-piece device. The new device is therefore in no way the inferior of its predecessor.

It is to be noted that the change from the old to the new is accomplished at a minimum of expense and with an easy replacement and without sacrificing any of the advantages or changing the mode of operation of the existing apparatus.

I do not wish to be restricted to the size, form and proportions of the various parts and obviously changes could be made in the construction herein described without departing from the spirit of the invention, it being only necessary that such changes fall within the scope of the appended claims.

What I claim is:

1. In combination with a vault or safe door, a mechanism for securing the door in closed position including in part a shaft journaled upon the door and having an eccentric pin, a removable block for engaging the eccentric pin, and a fixture for removably holding the block adjacent the safe door.

2. In combination with a vault or safe door and closing apparatus therefor, a device for holding the door closed, comprising

a socket member adapted to be affixed adjacent the door and having a socket therein open from above and closed at its bottom with a slot in its front wall, a block element 5 having a slot to receive the door closing apparatus and provided with flanges received in the socket member.

3. In combination, a door panel, a door hinged thereto, locking mechanism for the 10 door, door closing mechanism including a shaft journaled upon the door and having projecting eccentric pins, means at the hinged side of the door for permanently engaging the eccentric pin at this side, a 15 slotted and flanged block to receive the eccentric pin at the opposite side and a socket member affixed to the panel for de-

tachably receiving said slotted and flanged block.

4. In combination with a vault or safe 20 door and closing apparatus therefor, a device secured to the vault for securing the door in closed position, said device including an essential cooperating part adapted to be removed when the vault or safe is open 25 to prevent unauthorized securing of the door in closed position.

In testimony whereof, I have affixed my signature in presence of two witnesses.

WALTER E. MURRAY.
